COMBINATION WATCH AND IDENTIFICATION TAG HOLDER

Harry Gibbons, Chicago, Ill., assignor of one-third to William Weinberg and one-third to Louis Zeinfeld, both of Chicago, Ill.

Application July 26, 1950, Serial No. 11,423

Term of patent 14 years

(Cl. D42—8)

To all whom it may concern:

Be it known that I, Harry Gibbons, a citizen of the United States of America and resident of Chicago, in the county of Cook and State of Illinois, have invented a new, original, and ornamental Design for a Combination Watch and Identification Tag Holder, of which the following is a specification, reference being had to the accompanying drawings, forming a part thereof.

Fig. 1 is a plan view of a combination watch and identification tag holder showing my new design.

Fig. 2 is a view of one side thereof.

Fig. 3 is an end view thereof.

Fig. 4 is a view of the other side thereof.

Fig. 5 is a bottom view thereof.

The essential features of my design reside in the parts shown in full lines and the fragments of a wrist band shown in broken lines in all of the figures are for illustrative purpose only.

I claim:

The ornamental design for a combination watch and identification tag holder, substantially as shown and described.

HARRY GIBBONS.
